BY *Atturum*

HIS ATTORNEY

UNITED STATES PATENT OFFICE.

JEAN FRÉDÉRIC SCHWEIZER-CAILLAUX, OF VINCENNES, FRANCE.

HAT-PROTECTOR.

1,373,713.

Specification of Letters Patent.

Patented Apr. 5, 1921.

Application filed October 31, 1919. Serial No. 334,692.

To all whom it may concern:

Be it known that I, JEAN FRÉDÉRIC SCHWEIZER-CAILLAUX, citizen of the Republic of Switzerland, residing at 130 Rue de 5 Paris, Vincennes, Seine, in the Republic of France, have invented new and useful Improvements in Hat-Protectors, of which the following is a specification.

This invention relates to a cover for protecting hats from rain.

The improved hat cover can be applied easily and readily on hats of different sizes and shapes so as to protect from the rain all the parts thereof which are liable to 15 be damaged. It is of a simple and easy construction and can be folded into a small space so that it may conveniently be carried by the wearer in a pocket or handbag when not in use.

20 In the accompanying drawing given by way of example:

Figure 1 is a sectional elevation along the line X—X of Fig. 2, showing a cover for hats constructed in accordance with the 25 invention.

Fig. 2 is an inverted plan view of the same.

Fig. 3 is a view similar to Fig. 2 showing the cover in position on a hat and illustrating also the securing means for the 30 same.

The improved cover is made of a waterproof fabric cut out and sewn so as to provide a top part 6 and a rim part 1. Wide 35 tapering teeth 2 are cut out in the rim 1 along its whole outer edge, the ends 3 of said teeth being folded down and sewn to the lower face of the rim so as to provide loops 5. A braid, string or ribbon 4 is in-

serted in said loops as shown in Figs. 2 40 and 3.

This device may be conveniently carried in a pocket when folded. In case of need, it is unfolded and secured upon the hat, the toothed edge overhanging the edge of 45 the rim. By simply pulling the two ends of the string 4 together, the toothed edge will be folded down under the rim as shown in Fig. 3 and the cover will be secured firmly in position upon the hat whereby the 50 latter will be protected in all of its parts which are liable to be damaged.

The cover can be made in an extremely simple manner. A blank comprising the top part 6 of the cover and the rim 1 is preferably cut out from the impervious material, the two elements are then separated, the rim is prepared as hereinbefore described and the side band 7 is finally secured by 55 sewing to the parts 1 and 6. 60

Having now described my invention, what I claim as new and desire to secure by Letters Patent is:

A hat cover of waterproof material, comprising a flexible cover body having tapering teeth formed at its outer edge, the ends of which teeth are folded down and secured to the cover so as to form loops, and a flexible member adapted to be inserted in said loops. 65

In testimony whereof I have signed my name to this specification in the presence of two subscribing witnesses.

JEAN FRÉDÉRIC SCHWEIZER-CAILLAUX.
